Patented Feb. 14, 1928.

1,659,436

UNITED STATES PATENT OFFICE.

RICHARD MARX, OF PHILADELPHIA, PENNSYLVANIA.

DEVICE FOR CUTTING WEFT THREADS OF WOVEN FABRICS.

Application filed March 25, 1925. Serial No. 18,169.

This invention relates to devices of the general character disclosed in U. S. Patent No. 1,496,241, dated June 3, 1924, and one object of the present invention is to provide a device for cutting the weft threads of a woven fabric so constructed as practically to insure the centering of the cutting elements, thereby affording a pile of maximum thickness requiring little shearing.

Another object of the invention is to provide a device of the stated type provided with improved adjustment features facilitating replacement of parts.

A further object of the invention is to provide a device of the stated character permitting the use of more cutters to the inch than heretofore has been practicable.

The invention also contemplates the provision of a novel cutting attachment for looms employing rotary cutters operating in conjunction with fixed guide elements as hereinafter described and as clearly illustrated in the attached drawings, in which:

Figures 1 and 2 are respectively a side elevation and a plan view of an assembled attachment made in accordance with my invention;

Fig. 3 is a section on the line 3—3, Fig. 1, and

Figs. 4 and 5 are respectively a side elevation and a plan view of one of the cutter guide elements.

With reference to the drawings, each of the cutting elements comprises a guide element 1, clearly illustrated in Figs. 4 and 5, consisting of a flat plate of hooked formation having a slotted portion 2 at the top terminating at the forward end in an extended tongue 3 and shaped to provide a guide for a flat rotary disk cutter 4, as shown in Figs. 1 to 3, the said cutter projecting into the slot 5, as clearly illustrated.

As a support for the elements, I provide a beam 6 adapted for mounting transversely of the loom. As clearly illustrated, the beam 6 has in one longitudinal side a recess 7 terminating short of each end, and across this recess I secure supporting bars 8 and 9 and a third bar 10 secured in the bottom of the recess inwardly of the said supporting bar 8. The bar 8 is provided in its top with parallel longitudinal recesses 11 and 12 adapted for reception of a depending lug 13 on each of the guide members 1. With the lug occupying one or other of the recesses 11 and 12, as shown in Fig. 3, and

with the tongue 3 extending inwardly across the recess 7 and over the top of the bar 10, the lower hooked end of the members 1 extend inwardly under the said bar 8, and retaining elements 14 in the form, for example, of rubber bands connect the members with the bar 9, the lower hooked ends of the members 1 being provided in each instance with a suitable recess 15 for the rubber bands and the bar 9 being provided in the present instance with suitable projecting elements 16 around which the lower ends of the connecting resilient bands extend. The bands 14, as will be apparent, tend to retain the elements 1 in their respective proper positions on the supporting structure, while at the same time providing a certain amount of resiliency and free movement of the said members.

As shown in Figs. 3 and 5, the outer ends of the tongues 3 of the members 1 are provided with a perforation 17 for reception of a guide wire 18, see Fig. 3, which passes through one of the heddles of the loom to which the cutter is attached.

Mounted at each end of the beam 6 is a bracket 21 constituting a support and guide for a slide 22 carrying a bearing for a shaft 23 upon which the cutter disks 4 are mounted. As illustrated, both the bracket 21 and the slide 22 are provided with a transverse flange, 24 and 25 respectively, and the flange 24 is provided with an aperture for a bolt 26 which is threaded into the flange 25, thereby constituting means for adjusting the slide 22 vertically on the bracket. A second bolt 27 passes through a vertical slot 28 in the upright portion of the bracket 21 and is threaded into the corresponding portion of the slide 22, the bolt 27 holding the slide 22 to the face of the bracket 21 and providing additional means for locking the slide in adjusted position to the bracket. Each slide 22 carries at its lower end a horizontal bearing 29 for the said shaft 23, and the cutter disks 4 are keyed to this shaft so as to rotate therewith, while maintaining freedom of movement axially.

The shaft 23 is so adjusted and the relation of parts is such that when the lug 13 occupies the groove 11 in the supporting bar 8 as shown in Fig. 3 the elements 1 and 4 occupy a cutting relation such that any weft threads passing inwardly over the tongue 17 will be brought into contact with the rotating cutter 4 and severed thereby. The arrange-

ment also permits the various guide elements 1 to be moved outwardly to a position in which the lug 13 occupies the outer groove 12 and in this position the cutter disk 4 lies clear of the slot 5. Obviously, the arrangement permits replacement of any one of the elements 1 without disturbing the normal cutting relation between the others of the cutters and the respective guide elements.

10 Under conditions of operation, the cutter shaft 23 is continuously rotated from any suitable source of power through the medium of a pulley 30 at one end of the shaft, and by means forming no part of the present invention,

15 the successive change of weft threads of the newly woven fabric is guided onto the tongues 3 of the elements 1 which as previously noted extend between the warp threads at any desired intervals. As the 20 fabric is moved rearwardly, the weft threads are brought successively into contact with the edge of the rotating cutter disks 4 and are immediately severed thereby.

It is obvious by reason of the floating 25 nature of the elements 1 and of the cooperating cutters and by reason further of the concentric relation of the elements 1 and cutter disks 4, the wefts will be accurately cut at their centers, giving a pile of maximum 30 thickness requiring very little shearing. The arrangement also provides for the use of a comparatively large number of cutters to the inch, and in this sense the device is a mate-

rial improvement over devices of like nature.

I claim:

35

1. In a cutter for use on pile fabric looms, the combination with a plurality of rotary cutter elements mounted for free axial movement, of a floating guide for each of said elements movable with the latter.

40

2. In a cutter for pile fabric looms, the combination with a shaft, of a plurality of rotary cutters splined to the shaft, and a plurality of floating guide elements each having a slot for reception of one of the cutter elements and movable with said elements axially of said shaft.

45

3. In a cutter for pile fabric looms, the combination with a supporting structure having a longitudinal groove, a plurality of guide elements having retaining portions extending in said groove, resilient means for retaining the guide elements in said groove, and a plurality of rotary cutter elements cooperative with the said guides.

50

4. In a cutter for pile fabric looms, the combination with a supporting structure having a longitudinal groove, of a plurality of slotted guide elements having parts extending into said groove, resilient means for retaining the guide elements in position, a shaft parallel to said groove, and a plurality of rotary cutter elements splined to said shaft and adapted for operation in the slots of said guide elements.

55

RICHARD MARX.
